[57] CLAIM

The ornamental design for a promotional storage compartment and business card holder with moveable dividers, shown and described.

DESCRIPTION

FIG. 1 is a front perspective view of the promotional storage compartment and business card holder with moveable dividers in accordance with my invention;

FIG. 2 is a front elevational view thereof;

FIG. 3 is a rear elevational view thereof;

FIG. 4 is a right side elevational view thereof (left side is a mirror image of right side);

FIG. 5 is a top plan view thereof;

FIG. 6 is a bottom plan view thereof; and,

FIG. 7 is a front perspective view thereof.

The counter fragment in FIG. 1 and the cards in FIG. 7 depicted by means of broken lines have been shown for illustrative purposes only and form no part of the claimed design.
